UNITED STATES PATENT OFFICE.

JOACHIM T. HOLTFOTH, OF HIGHLAND PARK, MICHIGAN, ASSIGNOR TO L. A. YOUNG INDUSTRIES, INCORPORATED, OF DETROIT, MICHIGAN.

CUSHION-SPRING-ASSEMBLING MACHINE.

Application filed May 15, 1922. Serial No. 561,192.

To all whom it may concern:

Be it known that I, JOACHIM T. HOLTFOTH, a citizen of the United States, residing at Highland Park, county of Wayne, State of Michigan, have invented certain new and useful Improvements in Cushion-Spring-Assembling Machines, of which the following is a specification.

This invention relates to improvements 10 in cushion spring assembling machines.

The objects of the invention are:

First, to provide an improved machine for assembling a plurality of cushion springs of the helically coiled type in supporting 15 strips of U-cross section thereby forming spring units adapted to be assembled in cushion structures such as those of automobile seats, bed springs and the like.

Second, to provide a machine of the class 20 described for assembling springs in which all of the springs in the unit are effectively secured to the end supporting strips.

Third, to provide a machine of the class 25 described having these advantages which is capable of a large output with a comparatively small amount of labor or effort on the part of the operator.

Fourth, to provide a structure of the class 30 described which is simple in structure and at the same time very strong and durable.

Further objects, and objects pertaining to 35 details and economies of construction and operation will definitely appear from the detailed description to follow.

I accomplish the objects of my invention by the devices and means described in the following specification. The invention is clearly defined and pointed out in the claims.

A structure which is a preferred embodiment 40 of my invention is fully illustrated in the accompanying drawing forming a part of this specification, in which:

Fig. I is a front elevation of my improved spring assembling machine.

Fig. II is a plan view with a series of 45 springs and their supports in position, the jaws being open to receive them, an assembling unit being also shown in position in the conforming mechanism.

Fig. III is an enlarged detail vertical 50 section on a line corresponding to line 3—3 of Fig. I showing details of the driving and operating mechanism.

Fig. IV is an enlarged detail view par-

tially in longitudinal section on a line cor- 55 responding to line 4—4 of Fig. I.

Fig. V is an enlarged detail view partially in vertical section on a line corresponding to line 5—5 of Fig. I showing details of the closing jaws and the actuating means there- 60 for.

Fig. VI is a fragmentary view correspond- 65 ing to that of Fig. V with the jaws in their closed position.

Fig. VII is a detail vertical section show- 70 ing the manner of clamping the supporting strips upon the springs.

Fig. VIII is a plan view of one of the 75 assembled units, the springs being partially broken away and the conformed position of the ends of the units being indicated by dotted lines.

Fig. IX is a detail plan view of the left 75 hand conforming mechanism, the parts being shown in normal position.

Fig. X is a view corresponding to that of Fig. IX with the parts in actuated position.

Fig. XI is a detail vertical section on a line corresponding to line 11—11 of Fig. I 80 showing details of the unit conforming mechanism, the parts being shown in their initial position, or in the position of Fig. IX.

Fig. XII is a vertical section correspond- 85 ing to that of Fig. XI with the parts in actuated position.

Fig. XIII is a detail vertical section on a line corresponding to line 13—13 of Fig. I 90 showing the details of the ejector mechanism, the parts being shown in initial position.

Fig. XIV is a detail section correspond- 95 ing to that of Fig. XIII showing the parts in actuated position.

Fig. XV is a perspective view of one of the closing or upsetting jaws.

In the drawing the sectional views are taken looking in the direction of the little arrows at the ends of the section lines and similar numerals of reference refer to similar parts throughout the several views.

Referring to the drawing, I provide a frame 1 comprising suitable uprights and cross pieces adapted to support the operating mechanism and the bed 2. The bed 2 has upper jaws 3 mounted thereon and a 105 swinging head 4 carrying the upper jaws 5. The head 4 is mounted on journals 6 and is provided with a forwardly projecting arm

7 connected by the link 8 to the actuating lever 9. The lever 9 is pivoted at 10 at the rear of the machine and is provided with a footpiece 11 for convenience in operation.

5 The upper jaws 3 and 5 face downwardly and are provided with face or die plates 12 removably secured thereto as by the screws 13. The jaws 3 and 5 are adjustably supported so as that they may be spaced according to the spacing desired for the springs. The bed 2 has longitudinal grooves 14' therein adapted to receive the heads of the jaw securing bolts 14. When the nuts 15 are loosened the bolts, with the jaws, may be 15 adjusted laterally, thereby permitting the desired spacing.

The lower movable jaws 16 are slidably mounted in the bed for vertical movement, suitable supporting ways being provided 20 therefor. These jaws 16 carry die or face plates 17 corresponding to the face plates 12, the plates 17 being secured to the jaws 16 by means of the clamping plates 18. Rear jaws 19 coacting with the jaws 5 are provided with face or die plates 17 secured by the clamping plates 18 as described.

The jaws 16 and 19 are supported and actuated by the links designated generally by the numeral 20. These links are made up of 30 sections including threaded parts 21 and the tubular parts 22 which telescope with the upper parts 23 of the links. Coiled springs 24 are arranged within the tubular parts to yieldingly support the parts 23. By adjusting the threaded parts 21 the tension of these springs may be regulated. The lower ends of the links are pivotally mounted at 25 on the thrust bar 26 extending across the machine centrally thereof and having rollers 30 27 resting on the eccentrics 28 on the driving shaft 30.

This driving shaft 30 is provided with a belt pulley 31 having jaws 32 adapted to engage the clutch member 33 which is 45 splined to the shaft. A clutch release lever 34 is mounted on the rockshaft 35 and provided with a cammed end 36 adapted to engage the collar 37 on the clutch member and release it, and also hold it normally in disengaged position. When this releasing lever is thrown upwardly or disengaged the springs 38 engage the clutch (see Figs. III and IV). A spring 39 connected to the arm 40 on the frame and to the clutch releasing lever holds 55 the lever normally in clutch releasing position. A pawl 41 on the actuating lever 9 is adapted to disengage the clutch lever 34 when the actuating lever is pressed downwardly. The coiled spring 42 holds the pawl in engaging position. The pawl 41 has a rounded end 43 while the clutch lever has a coacting rounded surface 44 so that the clutch lever is disengaged and the pawl passes beyond the same on the actuation of 60 the lever 9. This allows the lever 34 to re-

turn to its clutch releasing position even though the footpiece 9 be held down by the operator. As the shaft 30 revolves the eccentric 28, acting upon the rollers 27 and, through them, upon the thrust bar, actuates 70 the movable jaws. However, before this action takes place the movable head 4 has been swung forwardly to bring the parts into proper assembled relation.

The supporting strips 45 are laid upon the lower jaws facing inwardly, these strips being of U-cross section as shown in Fig. V. The bottom jaws are provided with locating pins 46 while the upper jaws have holes 47 adapted to receive these pins 46 when the jaws are closed. The coiled springs 48 are positioned upon the spring supporting plates 49 which are provided with locating pins 50 adapted to engage the bottom coils of the springs. These spring supporting plates are 85 adjustably mounted on the plate bar 51 having a longitudinal slot 52 therein adapted to receive the bolts 53. This permits the adjustment of the spring supporting plates 90 to correspond with the jaws, whereby the machine may be adapted to different spacing.

In the use of the machine the strips 45 are first placed in position. The springs are then placed with their coils engaged with the front strip. When the springs are all 95 located the operator presses downwardly upon the lever 11 which swings the head 4 forwardly, bringing the rear strip over the bottom coils as shown by dotted lines in Fig. V. The clutch is also engaged as described, the engagement of the clutch and actuation of the thrust bar being properly timed so that the jaws 16 and 19 are not actuated until after the rear strip has been 100 engaged with the springs, the closing of the jaws upsetting or closing the strips upon the springs as shown in Fig. VII. A complete assembled unit is illustrated in Fig. VIII. Upon the releasing of the lever 11 the head 4 swings back to initial position 110 and the clutch is automatically released as described, leaving the jaws open. The jaw or die plates are preferably made reversible which materially increases the life or use thereof.

It is desired that ends of certain of the spring units should be curved as shown by dotted lines in Fig. VIII and by full lines in Fig. X, such spring units being used, for instance, at the ends of cushions where 115 curved corners are provided. To facilitate the conforming of these units as thus indicated, I provide a pair of spaced bed plates 54 on which the spring units may be placed as shown in Fig. II. At the outer end of each bed plate is mounted a slide 55 carrying the form blocks 56 having curved faces 57. The bed plates 54 are provided with form blocks 58 having curved faces 59 and the adjustable rest 60 and form block 61. The 120 125 130

slides 55 have adjustable thrust members 62.

With the parts in their initial position as shown in Fig. IX the assembled spring unit may be laid upon the bed plates 54, the form blocks and rests being arranged so that the units may be freely positioned. The slides 55 are actuated by the lever 63 pivoted at 64 to be actuated by the cam 65 on the shaft 66. The shaft 66 is connected to the shaft 30 by means of the sprocket chain 67 and suitable sprocket wheels. As the shaft 66 revolves, the cam 65 actuates the slide carrying the form block 56 into engagement with the end of the inner spring supporting strip and carrying the spring supporting strip against the form block 61 mounted on the table, and the rest 60, and also carrying the outer strip against the curved form block 58. The thrust member 62 engages the inner side of the outer strip bending it around the form block 58.

With the parts thus arranged both ends of the assembled unit are bent or conformed as may be desired. The levers 63 are held yieldingly against the cam 65 by means of the coiled springs 63'.

To automatically eject the conformed spring units I provide a pair of elevating members 68 which are adapted to lift the units above the form blocks 58 as shown in Fig. XIV. These elevating members 68 are provided with shanks 69 projecting downwardly through the bed members 54 to coact with the cams 70 on the shaft 66, the elevating members 68 normally resting in groove-like recesses in the bed pieces. The completed units are ejected or thrown from the elevating members by means of the ejector levers 71 which are pivoted at 72 and actuated by the spring 73. The cam 74 on the shaft 66 retracts these ejector levers.

With the parts thus arranged, when the bending operation has been completed, the members 68 are actuated to raise the spring units above the form blocks and the ejector is actuated to throw off or eject the completed unit as shown in Fig. XIV.

By the aid of my improved spring assembling machine the spring units may be rapidly assembled and the strips are effectively clamped upon the springs. To do this work by hand requires heavy labor and considerable time. The assembled units may be placed by the operator in the position to have the ends conformed and the conforming or bending is entirely automatic.

I have illustrated and described my improvements in an embodiment which I have found to be very practical. I have not attempted to illustrate or describe various modifications in structural details which might be desirable for different classes or kinds of work as I believe the disclosure made will enable those skilled in the art to which my invention relates to embody or

adapt the improvements as may be desired.

Having thus described my invention what I claim as new and desire to secure by Letters Patent is:

1. In a structure of the class described, the combination with the frame, of a bed mounted thereon, a swinging head mounted on said bed, sets of relatively fixed upper jaws adjustably mounted on said bed and on said head, a spring supporting bar disposed in a plane between said sets of jaws, spring supporting plates adjustably mounted on said bar, sets of lower jaws movably mounted on said bed and head to coact with said upper jaws, actuating links for said lower jaws, a thrust bar on which said links are pivotally mounted, a driving shaft provided with actuating eccentrics for said thrust bar, driving means for said shaft including a clutch, an actuating lever, connections therefor to said head whereby the head is actuated to move the jaws mounted thereon towards the jaws mounted on said bed, and clutch control means operatively associated with said actuating lever. 90

2. In a structure of the class described, the combination with the frame, of a bed mounted thereon, a swinging head mounted on said bed, sets of relatively fixed upper jaws mounted on said bed and on said head, a spring supporting bar disposed in a plane between said sets of jaws, spring supporting plates mounted on said bar, sets of lower jaws movably mounted on said bed and head to coact with said upper jaws, 100 actuating links for said lower jaws, a thrust bar on which said links are pivotally mounted, a driving shaft provided with actuating eccentrics for said thrust bar, driving means for said shaft including a clutch, an actuating lever, connections therefor to said head whereby the head is actuated to move the jaws mounted thereon towards the jaws mounted on said bed, and clutch control means operatively associated with said actuating lever. 110

3. In a structure of the class described, the combination with the frame, of a bed mounted thereon, a swinging head mounted on said bed, sets of relatively fixed upper jaws mounted on said bed and on said head, a spring supporting bar disposed in a plane between said sets of jaws, spring supporting plates mounted on said bar, sets of lower jaws movably mounted on said bed and head to coact with said upper jaws, adjustable actuating links for said lower jaws including thrust springs, a thrust bar on which said links are pivotally mounted, a driving shaft provided with actuating eccentrics for said thrust bar, driving means for said shaft including a clutch, an actuating lever, connections therefor to said head whereby the head is actuated to move the jaws mounted thereon towards the jaws mounted on 130

said bed, and clutch control means operatively associated with said actuating lever.

4. In a structure of the class described, the combination with the frame, of a bed mounted thereon, a swinging head mounted on said bed, sets of relatively fixed upper jaws adjustably mounted on said bed and on said head, a spring supporting bar disposed in a plane between said sets of jaws, 10 spring supporting plates adjustably mounted on said bar, sets of lower jaws movably mounted on said bed and head to coact with said upper jaws, actuating links for said lower jaws including thrust springs, a 15 thrust bar on which said links are pivotally mounted, and means for actuating said head and said bar timed so that the head is actuated prior to the actuating of the said bar.

5. In a structure of the class described, 20 the combination with the frame, of a bed mounted thereon, a swinging head mounted on said bed, sets of relatively fixed upper jaws mounted on said bed and on said head, a spring supporting bar disposed in a plane 25 between said sets of jaws, spring supporting plates mounted on said bar, sets of lower jaws movably mounted on said bed and head to coact with said upper jaws, actuating links for said lower jaws including 30 thrust springs, a thrust bar on which said links are pivotally mounted, and means for actuating said head and said bar timed so that the head is actuated prior to the actuating of the said bar.

35 6. In a structure of the class described, the combination with the frame, of a bed mounted thereon, a swinging head mounted on said bed, sets of relatively fixed upper jaws mounted on said bed and on said head, 40 a spring supporting bar disposed in a plane between said sets of jaws, spring supporting plates mounted on said bar, sets of lower jaws movably mounted on said bed and head to coact with said upper jaws, adjustable 45 actuating links for said lower jaws, a thrust bar on which said links are pivotally mounted, and means for actuating said head and said bar timed so that the head is actuated prior to the actuating of the 50 said bar.

7. In a structure of the class described, the combination of a bed, a head movable laterally relative thereto, relatively fixed upper jaws adjustably mounted on said head and bed, means for supporting springs between said sets of jaws including adjustable spring supporting plates, lower jaws movably mounted on said bed and head to coact with said upper jaws, actuating 55 means for said lower jaws, and actuating means for said head.

8. In a structure of the class described, the combination of a bed, a head movable laterally relative thereto, relatively fixed upper jaws mounted on said head and bed,

means for supporting springs between said sets of jaws, lower jaws movably mounted on said bed and head to coact with said upper jaws, actuating means for said lower jaws, and actuating means for said head.

9. In a structure of the class described, the combination of a bed, a head movable laterally relative thereto, relatively fixed upper jaws mounted on said head and bed, means for supporting springs between said sets of jaws, lower jaws movably mounted on said bed and head to coact with said upper jaws, actuating means for said lower jaws including thrust springs, and actuating means for said head.

10. In a structure of the class described, the combination of a bed, a head movable laterally relative thereto, relatively fixed upper jaws mounted on said head and bed, means for supporting springs between said sets of jaws, lower jaws movably mounted on said bed and head to coact with said upper jaws, actuating means for said lower jaws including thrust springs, actuating means for said head, and operating connections for said actuating means whereby the head is actuated prior to the actuation of said movable jaws.

11. In a structure of the class described, the combination of coacting jaws, at least one jaw of each pair being movable relative to the other and one pair of jaws being movable to and from the other pair, a spring supporting means disposed between the pairs of jaws whereby the spring supporting strips may be adjusted to the coils of the springs by the movement of the pairs of jaws, and operating connections whereby the movable pair of jaws is actuated prior to the closing of the jaws, for the purpose specified.

12. In a structure of the class described, the combination of coacting jaws, at least one jaw of each pair being movable relative to the other and one pair of jaws being movable to and from the other pair, a spring supporting means disposed between the pairs of jaws whereby the spring supporting strips may be adjusted to the coils of the springs by the movement of the pairs of jaws toward each other, and means for closing the jaws, for the purpose specified.

13. In a structure of the class described, the combination of a pair of spaced bedplates provided with outer forming blocks having curved faces adapted to coact with the outer side of the outer spring unit strip and with rest members adapted to coact with the inner side of the inner spring unit strip, forming slides mounted on said bedplates to reciprocate transversely of the spring units and having forming blocks with curved faces mounted on their inner ends to coact with the outer side of the inner spring unit strips, said slides also having

thrust members mounted thereon to engage the inner side of the outer spring unit strips adjacent the ends thereof, levers for reciprocating said forming slides, elevating members mounted on said bedplates adapted when actuated to raise the spring unit above said outer forming blocks, an ejector lever adapted to push the units from the said elevating members, a shaft disposed below said bed plates, and cams on said shaft for actuating said slide levers, said elevating members and said ejector levers successively.

14. In a structure of the class described, the combination of a pair of spaced bed plates provided with outer forming blocks having curved faces adapted to coact with the outer side of the outer spring unit strip and with rest members adapted to coact with the inner side of the inner spring unit strip, forming slides mounted on said bedplates to reciprocate transversely of the spring units and having forming blocks with curved faces mounted on their inner ends to coact with the outer side of the inner spring unit strips, said slides also having thrust members mounted thereon to engage the inner side of the outer spring unit strips adjacent the ends thereof, and means for reciprocating said forming slides.

15. In a structure of the class described, the combination of a pair of spaced bed plates provided with outer forming blocks having curved faces adapted to coact with the outer side of the outer spring unit strip and with adjustable rest members adapted to coact with the inner side of the inner spring unit strip, forming slides mounted on said bedplates to reciprocate transversely of the spring units and having forming blocks with curved faces mounted on their inner ends to coact with the outer side of the inner spring unit strips, said slides also having adjustable thrust members mounted thereon to engage the inner side of the outer spring unit strips adjacent the

ends thereof, and means for reciprocating said forming slides.

16. In a structure of the class described, the combination of a pair of spaced bedplates provided with outer forming blocks 50 adapted to coact with the outer side of the outer spring unit strip and with rest members adapted to coact with the inner side of the inner spring unit strip, forming slides mounted on said bedplates to reciprocate 55 transversely of the spring units and having forming blocks mounted on their inner ends to coact with the outer side of the inner spring unit strips, said slides also having thrust members mounted thereon to engage 60 the inner side of the outer strips adjacent the ends thereof, means for reciprocating said forming slides, elevating members mounted on said bedplates adapted when actuated to raise the spring unit above said 65 outer forming blocks, an ejector adapted to push the units from the said elevating members, and means for actuating said slides, said elevating members and said ejector successively.

17. In a structure of the class described, the combination of a pair of spaced bed plates provided with outer forming blocks adapted to coact with the outer side of the outer spring unit strip and with rest members adapted to coact with the inner side of the inner spring unit strip, forming slides mounted on said bedplates to reciprocate 75 transversely of the spring units and having forming blocks mounted on their inner ends 80 to coact with the outer side of the inner spring unit strips, said slides also having thrust members mounted thereon to engage the inner side of the outer strips adjacent the ends thereof, and means for reciprocating 85 said forming slides.

In witness whereof, I have hereunto set my hand and seal.

JOACHIM T. HOLTFOTH. [L.S.]
